[57] CLAIM

The ornamental design for an organ, substantially as shown and described.

DESCRIPTION

FIG. 1 is a front, top and left side perspective view of an organ showing my new design;

FIG. 2 is a front elevational view; and

FIG. 3 is a right side elevational view.

FIG. 4 is a view like FIG. 1 of a modified form of an organ showing my new design, wherein the music desk outline shape and ornamentation have been changed; FIG. 5 is a front elevational view of the music desk of FIG. 4; and

FIG. 6 is a side elevational view thereof.

The back of the music desk is plain and unornamented. The fabric covering the lower front broad and sides is continuous throughout the boundaries thereof.
